UNITED STATES PATENT OFFICE.

OLOF N. TEVANDER, OF CHICAGO, ILLINOIS, ASSIGNOR TO STANDARD CAP & SEAL CORPORATION, OF CHICAGO, ILLINOIS, A CORPORATION OF VIRGINIA.

CLOSURE-APPLYING MACHINE.

Application filed July 21, 1926. Serial No. 123,937.

My invention relates to machines for applying closures to containers and finds a very useful embodiment in a machine constructed to apply skirted caps to the beaded mouths of milk bottles, though the invention is not to be limited to this particular utility.

In my Patent 1,481,341, dated October 10, 1922, a machine is disclosed for wrapping a string about the skirts of closure caps, such machine including mechanism whereby clips are passed about the lapping ends of the string to fasten these ends together while the string is taut to maintain the assembly of the caps and the receptacles to whose mouth portions the caps are applied. In carrying out my invention I employ a positioner for a bottle having a skirted closure cap, mechanism constructed to contract the cap skirt about the neck of the bottle, and mechanism for cementing the cap skirt in contracted condition inclusive of means for fluxing cementitious material employed for this purpose and following the contraction of the cap skirt, said positioner and mechanisms being relatively adjustable into cooperative relation. The cap skirts are preferably supplied with contracting rings or strands desirably after the caps are applied to the bottles, the fluxing means serving to flux adjacent portions of the strand into assembly to hold the strand taut. The machine of my invention preferably employs means for supplying solder or other cementitious material and is not to be limited to its use in connection with any particular means or construction whereby the skirts of caps may be held in contracted relation about the necks of bottles.

The machine of my present invention is preferably inclusive of mechanism whereby cement is applied to the ends of a strand of string that is placed about the skirt of the closure cap. Cement is employed which will flux in response to a fluxing agency and which will harden, after being fluxed, to maintain the string in closure contracting relation. The strand of string employed is preferably circular in cross-section, and is preferably provided with the cement before it is employed in the machine. The cement employed is preferably solder in which case the string is desirably metallic. If solder is employed as a cement, the fluxing agency is heat which is preferably furnished by an electric current which is conducted by the

solder to be heated thereby. By making the string of metal, the string also may convey the heating current to the solder. After the current has been passed through the solder or through the string, if metal, or through both, a sufficient length of time to flux the solder, the current is discontinued and the solder is allowed to cool while the string is drawn tautly about the bottle cap, whereby the string is held in tight cap contracting relation to maintain the cap in firm assembly with the bottle to guard against the removal of the cap and to seal the bottle. A machine constructed in accordance with the preferred embodiment of my invention is adapted to produce the product claimed in my co-pending application Serial No. 110,447, filed May 20, 1926.

The invention will be more fully explained in connection with the accompanying drawings in which Fig. 1 is an elevation of the preferred form of machine, parts being shown in section; Fig. 2 is a view of a part of the mechanism shown in Fig. 1 in the direction of arrow 2; Fig. 3 is a view on line 3—3 of Fig. 1; Fig. 4 is a view on line 4—4 of Fig. 1; Fig. 5 is a view on line 5—5 of Fig. 1; Fig. 6 is a view on line 6—6 of Fig. 1; Fig. 7 is a view in elevation of a part of the mechanism which is shown in Fig. 6; Fig. 8 and Fig. 8^a, taken together, illustrate a view in elevation with parts shown in section and parts in full elevation, the bottom of Fig. 8 matching with the top of Fig. 8^a; Fig. 9 is a sectional view on line 9—9 of Fig. 8; Fig. 10 is a sectional view on line 10—10 of Fig. 8; Fig. 11 is a sectional view on line 11—11 of Fig. 8, the bottle and the cap skirt being shown in section for clearness in illustration; Fig. 12 is a view on line 12—12 of Fig. 13; Fig. 13 is a view on line 13—13 of Fig. 6 with parts omitted; Fig. 14 is a view on line 14—14 of Fig. 11; Fig. 15 is a view of a part of the mechanism looking in the direction of arrow 15 of Fig. 12; Fig. 16 is a sectional view of a part of the bottle illustrating the union between the lapping ends of the string; Fig. 17 is a sectional view on line 17—17 of Fig. 7; Fig. 18 is a sectional view on line 18—18 of Fig. 7 and looking in the direction of arrow 18 of Fig. 17; Fig. 19 is a view similar to Fig. 18 showing parts in changed positions; Fig. 20 is a sectional view on line 20—20 of Fig. 11 with parts in changed positions; and Fig. 21

is a view in elevation of the upper portion of a bottle with a closure cap as applied thereto by the machine.

The bottles 1 are suitably supplied to a stationary deck 2 carried upon posts 3 which are supported by the base 4 of the machine. These bottles have caps 5 initially loosely applied thereto, these caps being desirably constructed as disclosed in United States Patent 1,117,147, dated November 10, 1914. The skirts of these caps are to be tightened about the bottle necks by the machine of my invention so as to underlie the beads 6 about the bottle mouths shown by dotted lines in Fig. 1 and in the broken illustration of the bottle appearing in Fig. 8. The bottles, with the loose caps thereon, are fed through the chute 7 in position to be engaged by the teeth of the star wheel 8 which serve to continue the travel of the bottles as they leave the chute and to direct the same individually onto the vertically adjustable sections 9 of a disc-like table 10, these table sections constituting bottle positioners. Any suitable mechanism may be employed for operating the various operating elements that are located above the deck 2. In the embodiment of the invention illustrated, an electric motor 11 may be employed for operating a main drive shaft 12. Power is transmitted to this drive shaft at adjustable speed through the intermediation of any suitable speed changing gearing 13. The shaft 12 has a worm 14 thereon which is in mesh with a worm wheel 15. This worm wheel is fixed upon a shaft 16 on which there are also fixed the spur gear 17 and the table 10. The shaft 16 is journaled at its upper end in a sleeve bearing 16' carried by a spider 16² which is mounted upon the upper ends of the rods 16³ that are secured at their lower ends upon the base 4. This spur gear is in mesh with another spur gear 18 that is fixed upon a shaft 19 upon which shaft is also fixed the star wheel 8.

The bottle supporting table 10 is constantly turned and while turning, the sections 9 thereof are gradually elevated from the plane, proper, of the table and gradually restored to this plane, the final capping operation that is to be described occurring when said table sections are in their upper limits of their movements.

I provide a stationary cam track 20 upon which cam rollers 21 travel, to rise and fall. Each table section 9 is assembled with a cam roller so as to rise and fall therewith. As illustrated, each table section 9 is carried at the upper end of a spring barrel 22. A piston 23 is within the lower end of the spring barrel and is normally held in fixed relation therewith by means of a spring 24 which abuts at its lower end upon the piston and at its upper end against the top end wall of the spring barrel. A link 25 con-

nects each piston 23 with one end of a bell crank 26 upon whose elbow the corresponding cam roller is journaled. The other end of this bell crank is pivoted upon arm 27 depending from a bearing support 28 which is fixed upon the shaft 16 and is located below the table 10.

As the shaft 16 turns, the cam rollers move bodily therewith over the cam track 20 to elevate and lower the table sections 9 to enable these table sections to function. As the shaft 16 and the parts thereon turn, the spring barrels 22 rise and fall due to the normally fixed relation of the pistons 23 therewith. These spring barrels are guided in their movement by bearings 29 in the bearing support 28. If, in the final capping operation, the bottles should encounter undue strain, the springs 24 will yield to prevent the bottles from breaking, the pistons 23 then rising in the spring barrels.

A support 30 is in normally fixed relation with the shaft 16. This support has splined connection with the shaft 16 as indicated at 31 whereby it may be permitted movement lengthwise of the shaft. A bevel gear 32 has a nut formation 32' screwed upon the shaft 16 and has tongue and groove connection with the support 30 so that this support may be elevated and lowered along the shaft. A bracket 33 is carried by the support 30 and carries one bearing for the shaft 34 of the bevel pinion 35, the other bearing 36 for this shaft being provided in the support 30. The outer end of the shaft 34 is squared, Fig. 1, so that the bevel pinion 35 may be turned by hand to turn the bevel gear 32 that meshes therewith to turn nut 32' to elevate or lower the support 30. By this means, the chucks 37 which are carried by the support 30 through the intermediation of mechanism to be described, and which are provided to receive the tops of the bottles, may be elevated or lowered to suit the heights of the bottles being operated upon by the machine. These chucks also constitute bottle positioners. Each table section 9 has a chuck 37 individual thereto and in vertical alignment therewith, each such table section and the chuck corresponding thereto cooperating to hold a bottle therebetween. A tapering guide 38 is interposed between each table section 9 and the chuck 37 individual to this table section, the guides being carried by brackets 39 that are carried by the support 30. The guides 38 serve to direct the upper ends of the bottles into the chucks 37 and also to gather the skirts of the caps about the bottle necks preparatory to the application of the tightening rings or bands about such cap skirts, in case these skirts flare too much.

Each cycle of operation occupies one revolution of the shaft 16 and support 30 and

commences with the deposit of a bottle upon the table section 9 that is to receive it. After the bottle has been received upon the table section 9 that is to carry it, the table 10 and the table sections 9 turn a few degrees before the particular table section 9, in question, commences to rise to permit of some preparatory mechanical automatically effected adjustments. The bottle, in being raised, has its mouth end brought snugly into the chuck 37 overlying the table section 9 that carries such bottle. The bottle raises a solid plunger 40 which extends into the chuck 37. Each plunger has a stem 41 which is mounted to slide in a sleeve 42 which rotates in vertically aligned bearings 43 and 44. Each bearing 43 is held in place by a set nut 45 which passes through a sleeve 46. This sleeve 46 is an integral part of a bracket 47 which is bolted upon the top side of the support 30. When a plunger 40 is raised by the bottle beneath it, the upper end of the plunger stem 41 lifts the floating disc 48 and is coaxial with the plunger and the plunger stem. The disc 48 carries three upright pins 49 that slide within guiding holes formed in the inturned upper end of the extension 50 of sleeve 42. The upper ends of said pins thereupon lift the collar 51 which is splined upon the shaft 52 which is coaxial with and fixed with respect to the sleeve 42, this shaft being directly fixed upon the upper end of the sleeve extension 50. The groove of the collar 51 receives pins 53 provided upon the yoke lever 54 which is intermediately pivoted upon the shaft 55 that is journaled at the top end of the bracket 47. There is such a lever 54 at each bottle position, each lever constituting a part of a wire or string winding mechanism, there being as many such winding mechanisms as there are bottle positions. The base end of each yoke lever 54 carries an abutment 56 which is pressed upon by an upwardly spring pressed upright pin plunger 57. The spring 58 which presses upwardly upon the pin 57 is bottomed at its lower end upon the sleeve 59 which is slidable upon the pin 57 and presses at its upper end, upon the yoke 60 which is secured to the pin 57 and to the upright rod 61 which is slidable within bearing sleeves 62 and 63 carried by the bracket 47. When the plunger stem 41 is raised, the lever yoke 54 is turned clockwise to depress the pin 57 against the force of the spring 58. When thus depressed, the rod 61 is depressed. The adjustable nut 64 upon the rod 61 thereupon presses, at its lower end, upon one end of the bell crank 65 which is pivoted at its elbow upon the bracket 47. The other end of the bell crank is thereupon withdrawn from engagement with the detaining lug 66 which is provided upon the upper end of the sleeve 59. The bell crank lever 65, which thus functions as a detent normally to hold the sleeve 59 in its upper position, is withdrawn from its detaining position by the downward movement of the rod 61 to permit the spring 58 to depress the sleeve 59. This adjustment of the bell crank lever is effected against the force of the restoring spring 67 which is anchored at one end to the bell crank lever and at the other end to the bracket 47.

A yoke 68 is carried by the sleeve 59 and itself carries pins 69 that are received within an annular groove formed in the clutch collar 70 that is splined upon the sleeve 42. Clutch collar 70 is formed with clutching formations upon each end thereof which are respectively complementary to the clutching formations upon the stationary clutch member 71, (constituting an extension of the bearing 43) and the rotatable clutch member 72. When the clutch collar or member 70 is in clutching engagement with stationary clutch member 71, said clutch collar is held from rotation so that the sleeve 42 is not then rotatable. The engagement of the members 70 and 71 is effected during the movement of the table section 9 from the time this table section has received a bottle and until such table section is about to be raised by the cam track 20. To this end, the sleeve 59 carries a cam member 59' which rides upon the roller 59² carried by the bracket 59³ which, in turn, is carried upon the normally stationary gear carrier 59⁴. This gear carrier is supported upon the non-rotating sleeve 59⁵ to which it is keyed, a thrust ball bearing structure 59⁶ intervening between the lower end of the sleeve and the support 30. A ring 59⁷ is screwed upon the lower end of the sleeve and a collar 59⁸ is secured upon the support 30 and overlies the ring to keep the sleeve 59⁵ from rising. This sleeve is held from rotating by means of a pin 59⁹ depending from the bearing 16' and which passes through and is in sliding relation with an arm 59¹⁰ provided upon the sleeve 59⁵. The members 70 and 72 are thus positively separated at the initiation of a cycle and are permitted to be engaged when the corresponding table section 9 rises providing there is a bottle upon this table section. If there is no bottle, the clutch member 70 will be held elevated by the detent lever 65 so that the cycle of operations, which is commenced by the inter-action of the elements 59' and 59², is not completed if the bottle is absent. When the clutch collar or member 70 is moved downwardly into clutching engagement with the clutch member 72, a result which occurs when a bottle lifts the corresponding plunger 40, said clutch collar is turned by said clutch member 72 to turn the sleeve 42. The clutch member 72 which is thus employed to drive the sleeve 42 is turned one and one-half times by the time the support 30 has turned 130

-- a half of a revolution and is turned a half of a revolution during, approximately, the last one-sixth of the revolution of said support 30, all as will more fully hereinafter appear.

The sleeve 42 is provided for winding a strand of wire or string 73 about the skirts of bottle caps. The wire is directed upon the skirts by being passed through a nozzle 74 which is carried upon the unattached portion 42' of sleeve 42. The discharge end of the nozzle is located sufficiently away from the axis of the plunger stem 42 as to enable the nozzle, in being revolved around the bottle cap, to suitably apply the wire or string 73 to the skirt thereof. Each chuck 37, which is individual to each table section 9, has a wire winding mechanism individual thereto. Each wire winding mechanism has a reel 75 which is journaled upon the upright shaft 76 that is coaxial with the shaft 52, the shaft 76 being secured to the upper end of a yoke 77 whose lower end is secured to the shaft 52 whereby the two shafts turn together with the sleeve 42. A spring 78 abuts against a washer 79 which is positioned by a nut 80 screwed upon the upper end of the corresponding shaft 76. The lower end of said spring 78 presses down upon the disc 81 that bears against the upper side of the reel 75 to hold the lower side of the reel against the flange 82 of the yoke 77. The reel 75 is thus prevented from turning with respect to the shafts 76 and 52 any faster than it is so turned by the wire 73 being withdrawn therefrom. The spring 78 also takes part in adjusting the tension upon the wire being wound about the bottle cap, the adjustment of the spring determining the degree of tightness of the winding of the wire about such cap. The wire 73 is passed from the corresponding reel 75 over the idler pulleys 83, 84 carried by the bracket 85 which is an integral part of the yoke 77. The wire, after having left the idler pulley 84, is passed through the upright guiding tube 86 which is fixed with respect to the sleeve 42 and which passes through this sleeve and the shaft 52. Said tube is disposed along side of the axis of rotation of said sleeve and is located between this axis and the nozzle 74. The wire, after issuing from the lower end of the tube, passes over the idler pulley 87 which is journaled upon the sleeve 42. The wire, after having passed through the pulley 87, passes over the guiding lug 88 carried by the nozzle 74, this lug directing the wire through the nozzle outlet opening 89. The wire, where it is about to enter the nozzle end 89, is pressed against a side of the nozzle by the block 90 which, in turn, is pressed upon by the leaf spring 91.

By mechanism to be presently described, the leading end portion of the wire which has passed through the nozzle, is clamped be-

tween the members 92 and 93 which constitute an anchorage for this leading end of the wire in order that the wire may be held, at one end, during the rotation of the nozzle, about the corresponding bottle neck, the wire thus remaining clamped while the nozzle turns one and one-half times about the bottle neck. The nozzle and the clamp thus constitutes strand holders. The clamping action effected by the members 92, 93 is accomplished at the initiation of a cycle of operations and during the time that the members 59', 59² interact to separate the clutch members 70 and 72. The clamping member 93 is stationary, being desirably part of the stationary tapering guide 38. The clamping member 92 is pivoted at 94 upon a bracket 95 that is carried by the guide 38. Said clamping member is formed with a slot 96 which receives the spherical end of a lever 97 which is intermediately journaled upon a shaft 98 that is itself journaled in bearings 99, 100 carried by the brackets 47 and 39 respectively. An arm 101 is fixed upon the shaft 98. The stem of a bolt 102 passes through the lever 97 and the arm 101 and is surrounded by a spring 103. This spring has one end in engagement with a washer 104 which is adjustable in position by a nut 90 screwed upon the stem of the bolt. The other end of the spring engages the arm 101 and presses the head of the bolt against the lever 97. The spring, when permitted to function, operates through the bolt, lever and arm to apply the clamping member 92 to the wire. One end of a lever arm 105 is secured to the top end of the shaft 98 and carries a cam roller 106 at its other end. This cam roller enters a cam slot 107 formed in a normally stationary cam 108 which is carried by the upper end of the non-rotating sleeve 59⁵. This cam slot is so shaped that the clamping member 92 will be applied just as soon as the cycle of operations is initiated and will remain applied until after the overlapping ring portions are cemented together and the cement is hardened. The wire is severed, at the wire nozzle, just before the clamping member 92 is released, which release occurs upon the arrival of the cam roller 106 at a suitably shaped portion of the cam slot 107 as indicated in Fig. 4. When the wire nozzle has been turned one and a half times about the bottle neck, the fluxing device is brought into operation, as will later appear.

The gearing for turning the clutch member 72 which turns the sleeve 42 through the intermediation of the clutch members 70 and 72, as hitherto described, is inclusive of a spiral gear 109 fixed upon and coaxial with the clutch member 72, a spiral gear 110 meshing with the gear 109 and fixed upon a shaft 111 which is journaled at its ends in the bracket 47 that bodily rotates with the support 30 carrying it, and the

stationary segmental spiral rack 112 which is coaxial with the shaft 16 and which is carried by the normally stationary gear carrier 59⁴. A space intervenes between the entering end of the rack 112 and the gear 110 at the commencement of the cycle of operations so that there will be no rotation of the wire nozzle 74 while the bottle is being elevated. The gear 110 is positively held from rotation until it enters into mesh with the rack 112 by means of the stationary feather 113 which passes through a radial slot in said gear. Previously to the meshing of the gear 110 with the rack 112, the clutch members 70 and 72 were engaged by the action of the elevated bottle. If there happens to be no bottle in place upon a particular table section 9, the clutch members 70 and 72 will not be coupled so that there will be no rotation at all of the wire nozzle during the travel of said table section 9 owing to the separation of said clutch members. A thrust ball bearing structure 114 is interposed between the clutch member 72 and the support 30, another thrust ball bearing structure 115 is interposed between the support 30 and the enlargement 42' of the sleeve 42, and a third thrust ball bearing structure 116 is interposed between the sleeve enlargement 42' and the top of the chuck 37. The ball bearing structure 116 prevents the rotating sleeve 42 from turning the chuck 37, the rotation of the bottle by said sleeve 42 thus being prevented. It is understood that the cycle of operations commences at the left hand side of the constantly rotating support 30. The wire nozzle revolving operation ceases when said support 30 has about completed one-half of a revolution, that is, when the gear 110 leaves the stationary rack 112 whereupon said gear receives another stationary feather 117 to guard against incidental rotation of said gear.

By mechanism which will be presently described, the lapping or crossing portions of the wire that has been passed about a bottle cap are soldered together, this soldering operation occurring during the initial portion of the engagement of the gear 110 with the feather 117, the cooling of the solder occurring during an ensuing portion of this engagement and the severing of the wire at the wire nozzle occurring during the concluding portion of such engagement as will hereinafter appear.

The cement employed is desirably one which will fuse in response to heat and is desirably in the nature of solder, as indicated at 118. The string is preferably metallic, particularly if the cement is in the nature of solder. The solder is desirably present upon and about the wire before the wire is employed in the machine. That is, the wire is so-called tinned wire and is supplied as such from the reels 75. The invention is not to be thus limited, however, nor is it to be limited to the soldering or cementing of lapping ring portions nor to the lapping of ring portions. By the winding mechanism which has been described, the wire is closely wrapped about the cap skirt about one and one-fifth times the circumference of the cap skirt so that there is provided a cap contracting ring having mutually lapping portions, Fig. 21, it being these mutually lapping portions that are soldered together by fluxing the solder that is on the wire and allowing the solder to cool to hold said lapping portions in ring contracting relation. The wire of the ring is continued beyond the soldered together mutually lapping portions of the ring so that the wire may be grasped, where unattached, to tear the mutually lapping portions of the ring apart when access is to be had to the bottle.

Where the cement is fluxed by heat and the heat is furnished by an electric current, I employ two contacts 119, 120 which project from metallic spring barrels 121, 122, these contacts being inwardly pressed toward the wire by springs 123 within said spring barrels. The spring barrels slide within insulating sleeves 124, 125 which are carried by and are in fixed relation to the guide 38, Fig. 12. The sleeves 124 and 125 are desirably so positioned that the contacts 119 and 120 are at the ends of the lapping portions of the wire ring that are to be soldered together. Current is passed through the circuit that includes the spring barrels 121, and 122 and the contacts 119 and 120 from the battery 126, mechanism being provided for withdrawing the contacts from engagement with the wire when the circuit has endured sufficiently long to melt the solder in order that the solder may be allowed to cool, these results occurring while the gear 110 still engages the feather 113. The mechanism for thus controlling the circuit is desirably inclusive of two arcuate contact bars 127 and 128 which are assembled by bolts 129 which pass through circular openings in bar 128 and the arcuate opening 130 in bar 127. These bars are suitably insulated from the bolts by means of the insulating sleeves 131 and the insulating washers 132, the sleeves 131 being shouldered to receive the bar 128, the reduced ends of these sleeves passing through the circular holes in this bar. The two bars may be relatively adjustable longitudinally of each other to regulate their aggregate length, the two bars being thus in effect a bar whose effected length is adjustable.

The mechanism for controlling the circuit is also inclusive of a single bar 133 which is mounted upon a yoke 134 by the aforesaid bolts 129. This yoke is carried by clamps

135 that are clamped to two of the rods 16⁸. By means of these clamps, the yoke 134 may be adjusted vertically to suit other adjustments that are made according to the size 10 of the bottles being operated upon. The bars 127 and 128 are also carried by the yoke 134 through the intermediation of the insulating sleeves 131 which have other reduced ends that are received in circular holes 10 in the bar 133. The bolts 129 after passing through the sleeves 131 pass through insulating washers 136 and are screwed into the cam extension 137 of the yoke 134. The bars are thus insulated from the 15 yoke 134 and the bar 133 is likewise thus insulated from bars 127, 128, the latter two bars being in electrical connection. An additional bolt 138 may be employed for directly assembling the far end of the 20 bar 133 with the yoke, this bar 138 being insulated from the yoke 134. The spring barrels 121, 122 are provided with shanks 139 of reduced diameter, these shanks being received in insulating sleeves 140 that are 25 provided in the cross head 141. The spring barrels are clamped in assembly with the cross head by means of nuts 142 which are screwed upon the outer threaded ends of the shanks of spring barrels. Wipers 143 and 30 144 are clamped into electrical and mechanical assembly with the spring barrels by means of nuts 145 that are also screwed upon the threaded ends of the shanks of spring barrels. The wiper 143 has sliding contact 35 with the arcuate contact bar 133. The wiper 144 has sliding contact with the arcuate contact bars 127, 128. A cam roller 146 is carried by the cross head 141 and is adapted to ride upon the cam 137. During the initial 40 portion of the engagement of the gear 110 with the feather 117, the cam roller 146 is in engagement with the cam 137 to press the cross head inwardly to engage the contacts with the wire. Current from a battery 45 operated by the resistance of the wire and its solder causes sufficient heat to melt the solder which fluxes where the wire laps. The duration of the circuit is adjusted by relatively adjusting the two bars 127 and 128, as will be 50 apparent. When the contact wiper 144 leaves the contact bar 127, the circuit is opened. The contacts are also separated at this time, a result which is accomplished by means of the spring 147 that surrounds the 55 post 148 which is screwed into the guide 38 and which has a head upon its outer end against which the spring thrusts the cross head when the cam roller 139 has left the cam 137. 60 After the circuit is opened, the gear 110 continues in engagement with the feather 117, the solder cooling after the circuit is opened. After the cooling of the solder has been completed which occurs near the termination of the engagement of the gear 110

and the feather 117, the wire is severed at the nozzle while still under tension between the wire nozzle and the clamp 92, 93.

The mechanism for severing the wire is inclusive of a normally stationary knife 149 and a swinging knife 150, these two knives together constituting a pair of shears. Both knives are carried upon the post 151 which is provided upon the end of a lever 152 which is journaled upon a shaft 153 carried upon a bracket 154 which is carried by a yoke 155. This yoke is carried by clamps 156 that are clamped upon two of the bars 16⁸ whereby the shears may be adjusted 70 vertically to suit the adjustment of the other parts that are made to suit the bottles being operated upon. The knife 150 is a part of a bell crank which is journaled at its elbow 157 upon the post 151. The end of the bell crank which is opposite the end where the knife 150 is formed moves between two stops 158 and 159 which are provided upon and within the hollow carrier 160 which is secured upon the yoke 155. When the support 75 30 turns sufficiently, the stop 158 approaches the knife 150, as indicated in Fig. 18 to sever the wire which is received between the two knives. When the wire has been severed, the stop 159 approaches the knife 150 to move this knife away, as indicated by full lines in Fig. 19 and by dotted lines in Fig. 85 17. The two knives are normally withdrawn from the path of the wire and are positioned to receive the wire between them when the wire is to be cut, the approach of the knives to the wire being shown by full lines in Figs. 17 and 18 and the removal of the knives from the wire being shown by full lines in Fig. 19 and dotted lines in Fig. 17. To this end, the lever 152 which carries the knives is 80 controlled by the spaced apart cams 161 and 162, these cams being provided upon the rotating support 30. The cam 161 first engages the cam extension 163 of the lever 152 to swing the knives into a position in which the wires will be between them whereupon the knives are brought together in the manner described and as illustrated in Figs. 17 and 18. When the wire has been cut, the knives are together 85 moved to their outer position away from the wire, the lever 152 being suitably swung for this purpose by the cam 162 which engages the cam 164 fixed upon the shaft 153 upon which the lever 152 is fixed. 90

Very shortly after the knives have been withdrawn, the gear 110 leaves the feather 117 whereupon this gear engages the arcuate segmental gear rack 165 which is carried by the gear carrier 59⁴ and is in the same plane 95 with the rack 112. During this engagement of the gear 110 with the rack 165, the wire nozzle is turned a half revolution to bring the end of the wire projecting from the wire nozzle between the clamping members 92, 93, whereupon this wire end is clamped in 100 110 115 120 125 130

- the manner hitherto described, this clamping operation occurring upon the initiation of the next cycle. After the wire cutting operation and before this clamping of the wire 5 is effected, the table section 9 carrying the bottle operated upon is lowered and the bottle is discharged from the machine, this discharge of the bottle being the conclusion of the cycle of operations under description.
- 10 This bottle is discharged by one of the teeth of the star wheel 166 which star wheel is secured to the table 10. The tooth of the star wheel that engages this bottle forces the bottle to leave the table 10 and causes 15 the bottle to enter the chute 167 that directs the bottle upon the deck 2 from which the bottle may be moved by an attendant.
- While the machine herein disclosed includes a bottle positioning table member 20 which travels with respect to a point in space to bring the bottle to various stations where the various operations may be performed, it is obvious that the invention involves the travel of the bottles relative to 25 the mechanisms that perform the various operations, whether the bottles travel with respect to a point in space or said mechanisms so travel.
- Changes may be made without departing 30 from the invention.
- Having thus described my invention, I claim:
1. The combination with a positioner for a bottle having a skirted closure cap; of mechanism constructed to contract a strand about the skirt of the cap; and mechanism constructed to flux cementitious material upon adjacent portions of the strand to hold the strand taut, said positioner and mechanisms being relatively adjustable into 35 cooperative relation.
  2. The combination with a positioner for a bottle having a skirted closure cap; of mechanism constructed to apply a contracting strand to the skirt of the cap; and mechanism constructed to flux cementitious material upon end portions of the strand, said positioner and mechanisms being relatively adjustable into cooperative relation.
  3. The combination with a positioner for a bottle having a skirted closure cap; of mechanism constructed to apply a contracting strand to the skirt of the cap and inclusive of means for making the strand taut; and mechanism constructed to flux cementitious material upon end portions of the strand while the strand is taut, said positioner and mechanisms being relatively adjustable into cooperative relation.
  4. The combination with a positioner for a bottle having a skirted closure cap; of mechanism constructed to apply a contracting strand to the skirt of the cap and inclusive of means for making the strand taut; mechanism constructed to flux cementitious 40 material upon end portions of the strand while the strand is taut; and mechanism constructed to separate the applied strand from the strand applying mechanism, said positioner and mechanisms being relatively adjustable into cooperative relation.
  5. The combination with a positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism constructed to flux cementitious material upon end portions of the strand while the strand is taut; and mechanism constructed to sever the strand at the nozzle and disengage the strand at said holder, said positioner and mechanisms being relatively adjustable into cooperative relation.
  6. The combination with a positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism constructed to flux cementitious material upon end portions of the strand while the strand is taut; mechanism constructed to sever the strand at the nozzle and disengage the strand at said holder; and mechanism constructed to restore the nozzle to its starting position, said positioner and mechanisms being relatively adjustable into cooperative relation.
  7. The combination with a positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism constructed to flux cementitious material upon end portions of the strand while the strand is taut; mechanism constructed to sever the strand at and beyond the nozzle and disengage the strand at said holder; mechanism constructed to restore the nozzle to its starting position; and mechanism for applying said holder to the strand end projecting from the nozzle, said positioner and mechanisms being relatively adjustable into cooperative relation.
  8. The combination with a positioner for a bottle having a skirted closure cap; of mechanism constructed to apply a contracting strand to the skirt of the cap and in-

- clusive of holders for holding the ends of the strand that is to be applied and means operating upon said holders for pulling the applied strand taut; mechanism constructed to flux cementitious material upon end portions of the strand while the strand is taut; and mechanism constructed to separate the applied strand from said holders, said positioner and mechanisms being relatively adjustable into cooperative relation.
9. The combination with a positioner for a bottle having a skirted closure cap; of mechanism constructed to contract a strand about the skirt of the cap; and mechanism constructed to apply fluxing heat to cementitious material, that will flux in response to heat, upon adjacent portions of the strand to hold the strand taut, said positioner and mechanisms being relatively adjustable into cooperative relation.
10. The combination with a vertically movable positioner for a bottle having a skirted closure cap; of mechanism constructed to apply a contracting strand to the skirt of the cap; mechanism constructed to flux cementitious material upon end portions of the strand; and mechanism operating to elevate the positioner in advance of the strand applying operation and for lowering the positioner following the fluxing, said positioner and mechanisms being relatively adjustable into cooperative relation.
11. The combination with a vertically movable positioner for a bottle having a skirted closure cap; of mechanism constructed to apply a contracting strand to the skirt of the cap and inclusive of means for making the strand taut; mechanism constructed to flux cementitious material upon end portions of the strand while the strand is taut; and mechanism operating to elevate the positioner in advance of the strand applying operation and for lowering the positioner following the fluxing, said positioner and mechanisms being relatively adjustable into cooperative relation.
12. The combination with a vertically movable positioner for a bottle having a skirted closure cap; of mechanism constructed to apply a contracting strand to the skirt of the cap and inclusive of means for making the strand taut; mechanism constructed to flux cementitious material upon end portions of the strand while the strand is taut; mechanism constructed to separate the applied strand from the strand applying mechanism; and mechanism operating to elevate the positioner in advance of the strand applying operation and for lowering the positioner following the separation of the strand, said positioner and mechanisms being relatively adjustable into cooperative relation.
13. The combination with a vertically movable positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism constructed to flux cementitious material upon end portions of the strand while the strand is taut; mechanism constructed to sever the strand at the nozzle and disengage the strand at said holder; and mechanism operating to elevate the positioner in advance of the strand applying operation and for lowering the positioner following the severing and disengagement of the strand, said positioner and mechanisms being relatively adjustable into cooperative relation.
14. The combination with a vertically movable positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism constructed to flux cementitious material upon end portions of the strand while the strand is taut; mechanism constructed to sever the strand at the nozzle and disengage the strand at said holder; mechanism operating to restore the nozzle to its starting position; and mechanism operating to elevate the positioner in advance of the strand applying operation and for lowering the positioner following the severing and disengagement of the strand, said positioner and mechanisms being relatively adjustable into cooperative relation.
15. The combination with a vertically movable positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism constructed to flux cementitious material upon end portions of the strand while the strand is taut; mechanism constructed to sever the strand at and beyond the nozzle and disengage the strand at said holder; mechanism constructed to restore the nozzle to its starting position; mechanism for applying said holder to the strand end projecting from the nozzle; and mechanism operating to elevate the positioner in advance of the strand applying operation and for lowering the positioner following the severing and disengagement of the strand, said positioner and

mechanisms being relatively adjustable into cooperative relation.

16. The combination with a vertically movable positioner for a bottle having a skirted closure cap; of mechanism constructed to apply a contracting strand to the skirt of the cap and inclusive of holders for holding the ends of the strand that is to be applied and means operating upon said holders for pulling the applied strand taut; mechanism constructed to flux cementitious material upon end portions of the strand while the strand is taut; mechanism constructed to separate the applied strand from said holders; and mechanism operating to elevate the positioner in advance of the strand applying operation and for lowering the positioner following the separation of the strand, said positioner and mechanisms being relatively adjustable into cooperative relation.

17. The combination with a positioner for a bottle having a skirted closure cap; of mechanism constructed to contract a strand about the skirt of the cap; and mechanism constructed to apply fluxing heat to cementitious material, that will flux in response to heat, upon adjacent portions of the strand to hold the strand taut, and inclusive of a heat producing electric circuit, said positioner and mechanisms being relatively adjustable into cooperative relation.

18. The combination with a positioner for a bottle having a skirted closure cap; of mechanism constructed to apply a contracting strand to the skirt of the cap; and mechanism for fluxing cementitious material upon end portions of the strand and inclusive of an electric circuit portion containing a source of current and a terminal part which is applicable to the region of the strand, said positioner and mechanisms being relatively adjustable into cooperative relation.

19. The combination with a positioner for a bottle having a skirted closure cap; of mechanism constructed to apply a contracting strand to the skirt of the cap and inclusive of means for making the strand taut; and mechanism for fluxing cementitious material upon end portions of the strand while the strand is taut and inclusive of an electric circuit portion containing a source of current and a terminal part which is applicable to the region of the strand, said positioner and mechanisms being relatively adjustable into cooperative relation.

20. The combination with a positioner for a bottle having a skirted closure cap; of mechanism constructed to apply a contracting strand to the skirt of the cap and inclusive of means for making the strand taut; mechanism for fluxing cementitious material upon end portions of the strand while the strand is taut and inclusive of an elec-

tric circuit portion containing a source of current and a terminal part which is applicable to the region of the strand; and mechanism constructed to separate the applied strand from the strand applying mechanism, said positioner and mechanisms being relatively adjustable into cooperative relation.

21. The combination with a positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism for fluxing cementitious material upon end portions of the strand while the strand is taut and inclusive of an electric circuit portion containing a source of current and a terminal part which is applicable to the region of the strand; and mechanism constructed to sever the strand at the nozzle and disengage the strand at said holder, said positioner and mechanisms being relatively adjustable into cooperative relation.

22. The combination with a positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism for fluxing cementitious material upon end portions of the strand while the strand is taut and inclusive of an electric circuit portion containing a source of current and a terminal part which is applicable to the region of the strand; mechanism constructed to sever the strand at the nozzle and disengage the strand at said holder, said positioner and mechanisms being relatively adjustable into cooperative relation.

23. The combination with a positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism for fluxing cementitious material upon end portions of the strand while the strand is taut and inclusive of an electric circuit portion containing a source of current and a terminal part which is applicable to the region of the strand; mechanism constructed to sever the strand at and be-

yond the nozzle and disengage the strand at said holder; mechanism constructed to restore the nozzle to its starting position; and mechanism for applying said holder to the strand end projecting from the nozzle, said positioner and mechanisms being relatively adjustable into cooperative relation.

24. The combination with a positioner for a bottle having a skirted closure cap; of mechanism constructed to apply a contracting strand to the skirt of the cap and inclusive of holders for holding the ends of the strand that is to be applied and means operating upon said holders for pulling the applied strand taut; mechanism for fluxing cementitious material upon end portions of the strand while the strand is taut and inclusive of an electric circuit portion containing a source of current and a terminal part which is applicable to the region of the strand; and mechanism constructed to separate the applied strand from said holders, said positioner and mechanisms being relatively adjustable into cooperative relation.
25. The combination with a vertically movable positioner for a bottle having a skirted closure cap; of mechanism constructed to apply a contracting strand to the skirt of the cap; mechanism for fluxing cementitious material upon end portions of the strand and inclusive of an electric circuit portion containing a source of current and a terminal part which is applicable to the region of the strand; and mechanism operating to elevate the positioner in advance of the strand applying operation and for lowering the positioner following the fluxing, said positioner and mechanisms being relatively adjustable into cooperative relation.

26. The combination with a vertically movable positioner for a bottle having a skirted closure cap; of mechanism constructed to apply a contracting strand to the skirt of the cap and inclusive of means for making the strand taut; mechanism for fluxing cementitious material upon end portions of the strand while the strand is taut and inclusive of an electric circuit portion containing a source of current and a terminal part which is applicable to the region of the strand; and mechanism operating to elevate the positioner in advance of the strand applying operation and for lowering the positioner following the fluxing, said positioner and mechanisms being relatively adjustable into cooperative relation.

27. The combination with a vertically movable positioner for a bottle having a skirted closure cap; of mechanism constructed to apply a contracting strand to the skirt of the cap and inclusive of means for making the strand taut; mechanism for fluxing cementitious material upon end portions

of the strand while the strand is taut and inclusive of an electric circuit portion containing a source of current and a terminal part which is applicable to the region of the strand; mechanism constructed to separate the applied strand from the strand applying mechanism; and mechanism operating to elevate the positioner in advance of the strand applying operation and for lowering the positioner following the separation of the strand, said positioner and mechanisms being relatively adjustable into cooperative relation.

28. The combination with a vertically movable positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism for fluxing cementitious material upon end portions of the strand while the strand is taut and inclusive of an electric circuit portion containing a source of current and a terminal part which is applicable to the region of the strand; mechanism constructed to sever the strand at the nozzle and disengage the strand at said holder; and mechanism operating to elevate the positioner in advance of the strand applying operation and for lowering the positioner following the severing and disengagement of the strand, said positioner and mechanisms being relatively adjustable into cooperative relation.

29. The combination with a vertically movable positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism for fluxing cementitious material upon end portions of the strand while the strand is taut and inclusive of an electric circuit portion containing a source of current and a terminal part which is applicable to the region of the strand; mechanism constructed to sever the strand at the nozzle and disengage the strand at said holder; mechanism constructed to restore the nozzle to its starting position; and mechanism operating to elevate the positioner in advance of the strand applying operation and for lowering the positioner following the severing and disengagement of the strand, said positioner and mechanisms being relatively adjustable into cooperative relation.

30. The combination with a vertically

- movable positioner for a bottle having a skirted closure cap; of winding mechanism constructed to wind a contracting strand about the skirt of the cap and inclusive of a nozzle mounted to turn about the cap skirt and through which a strand is fed, and a holder for engaging the leading end of the strand, said nozzle and holder cooperating to make the strand taut; mechanism for fluxing cementitious material upon end portions of the strand while the strand is taut and inclusive of an electric circuit portion containing a source of current and a terminal part which is applicable to the region of the strand; mechanism constructed to sever the strand at and beyond the nozzle and disengage the strand at said holder; mechanism constructed to restore the nozzle to its starting position; mechanism for applying said holder to the strand end projecting from the nozzle; and mechanism operating to elevate the positioner in advance of the strand applying operation and for lowering the positioner following the severing and disengagement of the strand, said positioner and mechanisms being relatively adjustable into cooperative relation. 31. The combination with a vertically movable positioner for a bottle having a skirted closure cap; of mechanism constructed to apply a contracting strand to the skirt of the cap and inclusive of holders for holding the ends of the strand that is to be applied and means operating upon said holders for pulling the applied strand taut; mechanism for fluxing cementitious material upon end portions of the strand while the strand is taut and inclusive of an electric circuit portion containing a source of current and a terminal part which is applicable to the region of the strand; mechanism constructed to separate the applied strand from said holders; and mechanism operating to elevate the positioner in advance of the strand applying operation and for lowering the positioner following the separation of the strand, said positioner and mechanisms being relatively adjustable into cooperative relation. 32. The combination with a bottle positioner; of mechanism constructed to place a strand upon the neck of a bottle positioned by the positioner; a pair of terminal contacts positioned to present their contacting ends in the region of the applied strand; a circuit portion containing a source of current and said contacts; and mechanism constructed to connect said contacts with said circuit portion, said positioner and mechanisms being relatively adjustable into cooperative relation. 33. The combination with a bottle positioner; of mechanism constructed to place a strand upon the neck of a bottle positioned by the positioner; a pair of movable terminal contacts positioned to present their contacting ends in the region of the applied strand; a circuit portion containing a source of current and said contacts; and mechanism constructed to move said contacts toward the applied strand; and mechanism constructed to connect said contacts with said circuit portion, said positioner and mechanisms being relatively adjustable into cooperative relation. 34. The combination with a bottle positioner; of mechanism constructed to place a strand upon the neck of a bottle positioned by the positioner; a circuit portion containing a source of current; a pair of movable terminal contacts provided for said circuit portion and positioned to present their contacting ends in the region of the applied strand; and mechanism constructed to move said contacts toward the applied strand, said positioner and mechanisms being relatively adjustable into cooperative relation. 35. The combination with a bottle positioner; of mechanism constructed to place a strand upon the neck of a bottle positioned by the positioner; a circuit portion containing a source of current; contact bars in which said circuit portion terminates; and a pair of contacts having contacting ends in the region of the applied strand and provided with contacting portions respectively engageable with said contact bars, said positioner being adjustable with respect to said mechanism and contact bars into cooperative relation therewith. 36. The combination with a bottle positioner; of mechanism constructed to place a strand upon the neck of a bottle positioned by the positioner; a circuit portion containing a source of current; contact bars in which said circuit portion terminates; a pair of movable contacts having contacting ends in the region of the applied strand and provided with contacting portions respectively engageable with said contact bars; and mechanism constructed to move said contacts toward the applied strand, said positioner being adjustable with respect to said mechanism and contact bars into cooperative relation therewith. 37. The combination with a bottle positioner; of mechanism constructed to place a strand upon the neck of a bottle positioned by the positioner; a circuit portion containing a source of current; contact bars in which said circuit portion terminates, the effective length of one of said contact bars being adjustable; and a pair of contacts having contacting ends in the region of the applied strand and provided with contacting portions respectively engageable with said contact bars, said positioner being adjustable with respect to said mechanism and contact bars into cooperative relation therewith.

38. The combination with a positioner for a bottle having a skirted closure cap; of mechanism constructed to contract the cap skirt about the neck of the bottle; and mechanism for cementing the cap skirt in contracted condition inclusive of means for fluxing cementitious material employed for this purpose and following the contraction of the cap skirt, said positioner and mechanisms being relatively adjustable into cooperative relation.

39. The combination with a positioner for a bottle having a skirted closure cap; of mechanism constructed to contract the cap skirt about the neck of the bottle; and mechanism for cementing the cap skirt in contracted condition inclusive of means for applying fluxing heat to cementitious material, which will flux in response to heat, employed for this purpose and following the contraction of the cap skirt, said positioner and mechanisms being relatively adjustable into cooperative relation.

40. The combination with a positioner for a bottle having a skirted closure cap; of mechanism constructed to contract the cap skirt about the neck of the bottle; and mechanism for cementing the cap skirt in contracted condition inclusive of a heat producing electric current furnishing heat to flux cementitious material, which will flux in response to heat, employed for this purpose and following the contraction of the cap skirt, said positioner and mechanisms being

relatively adjustable into cooperative relation.

41. The combination with a positioner for a bottle having a skirted closure cap; of mechanism constructed to contract a strand about the skirt of the cap; and mechanism constructed to flux adjacent portions of the strand into assembly to hold the strand taut, said positioner and mechanisms being relatively adjustable into cooperative relation.

42. The combination with a positioner for a bottle having a skirted closure cap; of mechanism constructed to contract a strand about the skirt of the cap; and mechanism constructed to apply fluxing heat to adjacent portions of the strand to flux these strand portions into assembly to hold the strand taut, said positioner and mechanisms being relatively adjustable into cooperative relation.

43. The combination with a positioner for a bottle having a skirted closure cap; of mechanism constructed to contract a strand about the skirt of the cap; and mechanism constructed to produce fluxing heat generating electric current and apply the produced fluxing heat to adjacent portions of the strand to flux these strand portions into assembly to hold the strand taut, said positioner and mechanisms being relatively adjustable into cooperative relation.

In witness whereof, I hereunto subscribe my name,

OLOF N. TEVANDER.
